LIFE PRESERVER

John J. Geiszler, Costa Mesa, Calif., assignor to U.S. Divers Co., Inc., Santa Ana, Calif., a corporation of California

Filed Feb. 24, 1964, Ser. No. 78,746

Term of patent 3½ years

(Cl. D71—1)

FIG. 1

FIG. 2

FIG. 3

It is understood that the cross hatching shown represents fabric and extends throughout the entire area of the life preserver.

I claim:

The ornamental design for a life preserver, substantially as shown and described.
